CLAIM

The ornamental design for a mobile device, as shown and described.

DESCRIPTION

FIG. 1 is a top, front, right side perspective view of a mobile phone showing a first embodiment of our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a cross section-view of the mobile device of FIG. 1 taken along line 8-8 in FIG. 2; FIG. 9 is a top, front, right side perspective view of a mobile phone showing a second embodiment of our new design; FIG. 10 is a front elevational view thereof; FIG. 11 is a rear elevational view thereof; FIG. 12 is a left side elevational view thereof; FIG. 13 is a right side elevational view thereof; FIG. 14 is a top plan view thereof; FIG. 15 is a bottom plan view thereof; and, FIG. 16 is a cross section-view of the mobile device of FIG. 9 taken along line 16-16 in FIG. 10. The broken lines in the figures illustrate environmental structure of the article and form no part of the claimed design.
